(57) **CLAIM**

The ornamental design for a charging post for floor washer, as shown and described.

DESCRIPTION

1. Charging post for floor washer
2. Charging post for floor washer

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

2.1 : Front

2.2 : Back

2.3 : Left

2.4 : Right

2.5 : Top

2.6 : Bottom

2.7 : Perspective

2.8 : Perspective

(Continued)

2.9 : Perspective

2.10 : Perspective

1.1 is a front view of a first charging post for floor washer; 1.2 is a back view thereof; 1.3 is a left view thereof; 1.4 is a right view thereof; 1.5 is a top view thereof; 1.6 is a bottom view thereof; 1.7 is a front top perspective view thereof; 1.8 is a back top perspective view thereof; 1.9 is another front top perspective view thereof; 1.10 is a back bottom perspective view thereof. The broken lines in the reproductions depict portions of the charging post for a floor washer that form no part of the claimed design.
